DESIGN FOR A SPECTACLE FRAME

Monroe B. Levoy, New York, N. Y.

Application March 29, 1946, Serial No. 128,052

Term of patent 3½ years

(Cl. D57—1)

To all whom it may concern:

Be it known that I, Monroe B. Levoy, a citizen of the United States, residing at New York, county of New York, and State of New York, have invented a new, original, and ornamental Design for Spectacle Frames, of which the following is a specification, reference being had to the accompanying drawing, forming a part thereof.

Fig. 1 is a perspective view of a spectacle frame, showing my new design, the temples being shown fragmentarily for convenience of illustration;

The essential features of my design reside in the specific types and arrangements of the jewels on a spectacle frame of the configuration as herein shown.

I claim:

The ornamental design for a spectacle frame, as shown and described.

MONROE B. LEVOY.
